UNITED STATES PATENT OFFICE.

THEODORE G. McGIRR, OF NEW YORK, N. Y., ASSIGNOR TO ACME WRAPPING MACHINE COMPANY, OF NEW YORK, N. Y., A CORPORATION OF NEW YORK.

WRAPPING AND LABELING MACHINE.

949,804.

Specification of Letters Patent. Patented Feb. 22, 1910.

Application filed February 2, 1909. Serial No. 475,690.

To all whom it may concern:

Be it known that I, THEODORE G. McGIRR, a citizen of the United States, residing at New York, in the county of New York, State 5 of New York, have invented a new and useful Wrapping and Labeling Machine, of which the following is a specification.

This invention relates to machines for wrapping and labeling articles.

One object of my invention is to simplify the construction and operation of wrapping and labeling machines, to increase the output, and to deliver the wrapped articles in a stacked form for convenience of removal 15 and packing.

Another object is to deliver, one by one, printed labels from a stack of such labels in such position that the same will be folded about the articles to be wrapped.

Another object is to apply gum or other adhesive to the label or outside wrapper and to fasten the same about an inner wrapper of the package in such wise as to cause the same to retain its folded or wrapped shape 25 or form.

Another object is to make the folding mechanism readily accessible in case of accident, or derangement for any cause, to any of its parts; other objects will hereinafter 30 appear.

My invention consists of features of construction arrangements and combinations of devices hereinafter described and more particularly pointed out in the appended claims.

My invention is embodied in the machine illustrated in the accompanying drawings, forming part of this specification, in which:

Figure 1, is a front elevation, with parts broken away and removed in order to show 40 the parts behind and to get the whole upon the sheet of drawing; Fig. 2, is a plan view; Fig. 3, is a plan view of the machine below the plane A—A of Fig. 1; Fig. 4, is a side elevation from the top in Fig. 2, of the label 45 feeding mechanism; Fig. 5, is a vertical central sectional view of the same; Fig. 6, is a detached view, partly in section, of the stacker device; Fig. 7, is a sectional view of the driving mechanism for the label feed; Fig. 8, is a detail view of the knife operating 50 mechanism; Fig. 9, is a view from underneath of the top folding mechanism; Fig. 10, shows at the right a front view of half the folding mechanism and at the left a side

elevation of the same; Fig. 11, is a detail view of a tucker-device; Fig. 12, is a sectional view of the pusher and bridge-piece; Fig. 13, is a plan view of the same; Fig. 14, is a perspective view showing the package, the wrapper and the label at the beginning of the folding operation; Fig. 15, shows the same in perspective after the sides and ends have been folded in as the plunger moves the parts downward; Fig. 16, shows the same in perspective at a further stage 60 of the downward motion; Fig. 17, shows the same in perspective at the completion of the downward motion; Fig. 18, shows the said parts in perspective as they appear at the completion of the first stage of the motion 70 of the horizontal tucker or plunger; Fig. 19, shows the same in perspective at the completion of the folding in of the forward ends of the wrapper during the horizontal motion of the package; Fig. 20, shows the same in perspective at the completion of the folding down of one side of the wrapper and label and Fig. 21, shows the completely wrapped article.

The reference, 2, marks fixed vertical 80 sides of the machine; these sides are united by tie rods, 3, and platforms or tables, 4, 5, hereinafter referred to. The articles to be wrapped are placed in the vertical guideway, 6, which has an open side, as shown in Fig. 2, to facilitate the insertion of the articles. This guideway, 6, rises from the table, 4, and is cut away on its two sides to permit the pusher *a* to push the lower-most article therefrom and under the plunger *b*. 90 The pusher or plunger *a* moves to and fro in the fixed guides *a'* attached to the table, 4, by screws or otherwise, and is provided with an underneath extension or lug *a''* which passes through a slot in the said 95 table, 4; to this underneath lug or extension *a''* is pivoted at, *a''*, a link, *a''*, whose other end is pivotally connected with the lever, *a''*. The lever, *a''*, is pivoted at, *a''*, to a collar, *a''*, fixed upon a tie rod, 3, and said 100 lever, *a''*, is provided at, *a''*, with a stud and roller which engages with the groove of a drum cam, *a''*, which is fast upon the driving shaft *D* upon the machine. The cam, *a''*, is shaped, proportioned and timed to 105 move the pusher *a* as hereinafter described.

The paper, or foil, or both, from which the wrappers are formed, is fed from rolls

by the mechanism shown, described and claimed in a companion application for Letters Patent filed Feb. 2, 1909, Serial No. 475,689; the rolls are not shown herein, but certain of the feed rolls are indicated at, *q*, with their gears, 7, 8, and ratchet, 9.

The wrappers are severed from the web or webs by the oscillatory knife, 10, which is pivoted at, 11, to the fixed frame-work of the machine and is provided with an arm, 12, and a stud and roller, 13, for engagement with the grooved cam, 14, mounted on the fixed shaft of the roller, *q*, and driven by sprocket chain, 15. The knife, 10, co-acts with the fixed edge or blade, 16, to sever the wrappers from the web or webs (see Fig. 8). The wrappers so severed from the webs are immediately underneath the head *b* of the vertically moving plunger above the mouth *c* of the first folding mechanism. The head *b* is carried by the rod *b'* which is guided in a vertical direction by the guides, *b*², which are attached to the frame work of the machine. The rod *b'* is connected by a pin and stud, *b*³, with a slotted arm or lever, *b*⁴, integral with or attached to a sleeve, *b*⁵, which is journaled upon a tie rod, 3, of the machine, the tie rod in this instance having collars attached thereto between which the said sleeve works. The said sleeve, *b*⁵, is provided with an arm, *b*⁶, to which the upper end of a pitman, *b*⁷, is attached. Preferably, the pitman, *b*⁷, is adjustable as to length. The lower end of said pitman is pivotally connected with an arm or lever, *b*⁸, which is fulcrumed at, *b*⁹, on a tie rod, 3, in the base of the machine, said pivot, *b*⁹, working between collars attached to the said tie rod by set screws or otherwise. The lever, *b*⁸, has a stud and roller, *b*¹⁰, thereon which co-acts with a cam groove in the disk, *b*¹¹, whereby the said lever, *b*⁸, is moved up and down in order to rock the lever, *b*⁴, and move the rod up and down to operate the plunger *b*.

In order to carry the labels across the mouth *c* aforesaid, the slide or pusher *a* has attached thereto, or is formed with, a bridge-piece, *a*⁹, over which the label-feeding devices hereinafter described feed the label while the said bridge-piece, *a*⁹, covers the said opening, and which bridge-piece is withdrawn from underneath the label on the return of the plunger *a* to the right in Fig. 2, whereby the label is left underneath the wrapper or wrappers cut off by the knife, 10, and on which cut-off wrapper or wrappers the plunger *a* has just deposited one of the articles to be wrapped. The relative position of the label, 1, wrapper *w* and article *p* at this time is indicated in Fig. 14. As the plunger *b* moves downward, it comes in contact with the article *p* and pushes it and its wrapper and label down through the said mouth *c* and the long sides of the wrapper

w and the label are folded against the edge of the article *p*, as indicated in Fig. 15, by the sides of the said mouth *c*; after which the end *w'* of the wrapper is folded in as indicated in Fig. 15, by the upper tuckers *c*', 70 shown more clearly in Fig. 10, thus producing the box-like structure shown in Fig. 15. As the plunger *b* moves the article further downward, the triangular corners *w*² are folded in from the position thereof shown in Fig. 15, to the position thereof shown in Fig. 16, by the scrolls, *c*², and thereafter during the further downward movement of the plunger, the corners, *w*³, of the wrapper are folded in from the position thereof shown in Fig. 16, to the position thereof shown in Fig. 17, by the scrolls *c*³. After passing through the scrolls, *c*², *c*³, the plunger *b* deposits the article, wrapped as shown in Fig. 17, on the table, 5, where the article 80 is held stationary by means of the spring, *c*⁴, which passes through the opening, *c*⁵, in one of the side uprights, *c*⁶. For convenience of access to the guideway formed by the walls, *c*⁶, two or more of the scrolls, *c*², *c*³, are 90 hinged at, *c*⁷, so that the same may be swung back to permit of access to the guideway formed by the said walls, *c*⁶, of the said scrolls. A keeper, *c*⁸, is hinged to one of the scrolls at, *c*⁹, and engages by a slot with a pin, *c*¹⁰, on the other scroll to lock the said scrolls in their closed or working positions, and frees them so they may be opened when it is lifted or turned upon its pivot to a sufficient extent to disengage it from the 100 pin, *c*¹⁰.

The partially wrapped article is next moved horizontally toward the stacker by devices now to be described. The table, 5, is slotted at, 17, to form a guideway for the 105 horizontally acting pusher *d* which has an arm extending down through the slot aforesaid, to which arm is pivotally connected at *d*' a link, *d*², whose other end is pivotally connected at, *d*³, with a lever, *d*⁴, which is 110 journaled upon a tie rod, 3, of the machine and is operated by a cam, *d*¹², on the shaft D aforesaid. The cam, *d*¹², operates the lever by means of a forked rod, *d*¹³, which straddles shaft D and carries a roller which 115 co-acts with the cam, *d*¹²; the rod, *d*¹³, is pivotally connected with lever *d*⁴.

The pusher *d* is formed to guide the tucker, *d*⁷, which slides upon the pusher *d* and is held forward in the position thereon indicated in Fig. 11, by means of a spring, *d*⁸, which surrounds a rod, *d*⁹, extending from the pusher *d* and provided with an adjustable abutment, *d*¹⁰, for said spring, the said spring abutting against the finger, 12 *d*⁷. The finger, *d*⁷, is provided with lugs or pins, *d*¹¹, which abut against the fixed part of the machine, as the standards or guides, *c*⁶, aforesaid, to arrest the said finger after the said finger has folded in the rear ends *w'*, 13

w^2 , w^3 , from the positions thereof shown in Fig. 17, to the positions thereof shown in Fig. 18, but the pusher d continues to advance and pushes the article onward into the channel e and under the vertical blades or tuckers, e' — e^2 , between which tuckers and the side walls of the channel the vertical or upstanding ends, l' , of the label and upstanding edges or sides, w^4 , of the wrapper or wrappers pass while the said tuckers e' , e^2 , fold in the leading ends, w^5 , from the positions thereof shown in Fig. 18, to the positions thereof shown in Fig. 19. Each successive partially wrapped article moved forward by the pusher d advances the partly wrapped article ahead of it along the said guideway or channel e and under the tuckers, e' , e^2 , and the sequence of the operations in such forward motion of the articles is as follows: After the forward ends are laid down as indicated in Fig. 19, the scroll, e^3 , lays down the narrower side of the label and wrapper from the position thereof shown in Fig. 19, to the position thereof shown in Fig. 20, after which the scroll, e^4 , lays down the wider side of the label and the wrapper from the position thereof shown in Fig. 20 to the position thereof shown in Fig. 21, and the said article then passes under the flat side, e^5 , of the scroll, e^4 , and into the stacker. During the progress of the partly wrapped article through the guideway e , gum or other suitable adhesive is applied to that part of the label which projects above the wrappers as shown in Figs. 15 to 20, and appliances for gumming the label will now be described:

Any suitable adhesive is placed in the receptacle or fountain g , which is attached to or is carried from the table, 5, by means of a bracket g' or otherwise. Above the fountain g is a rotatory shaft, g^2 , having fixed thereon a gear, g^3 , which meshes with the gear, g^4 , on the fixed frame-work of the machine. The gear, g^4 , is driven, in the instance shown, from the shaft D by a sprocket gearing, g^5 . Partly inside the fountain g is a disk, g^6 , which is fast upon the shaft, g^2 , aforesaid, and scrapers, g^7 , are attached to the fountain at that side thereof where the said disk, g^6 , rises out of the mass of adhesive, the function of the said scrapers being to prevent the disk from carrying around with it more than a thin film of the said adhesive substance. Outside the fountain, the said shaft, g^2 , has fixed thereto a beveled gear, g^8 , which meshes with a similar gear, g^9 , journaled on the bracket, g^{10} . Immediately above the beveled gear, g^9 , is a disk, g^{11} , which is attached to said gear and the periphery of which disk rubs or bears lightly against the face of the disk, g^6 , aforesaid to take adhesive therefrom. The disk, g^{11} , transfers the adhesive to a second disk, g^{12} , also journaled in the bracket, g^{10} .

The disks, g^{11} and g^{12} , are geared together by spur gears, g^{13} .

The aforesaid long upstanding side of the label, 1, bears against the periphery of the disk, g^{12} , as the articles pass along the passageway e aforesaid and takes adhesive from said disk, and when the said long side of the label is laid down upon the article as indicated in Fig. 21, the label is gummed to itself to form an external wrapper which holds down the wrapper w aforesaid. It is noted that by having the disk, g^{11} , run at a rate of speed different from that of the disk, d^6 , where the two touch each other, and by having the disk, g^{12} , also run at a rate of speed different from that of disk, g^{11} , the transfer of gum from one to another disk is facilitated, as there ensues a wiping action of one disk on the other.

The wrapped articles delivered from the passageway e are delivered one by one at intervals to a stacking apparatus now to be described. Attached to an extension of the table, 5, is a vertical guideway f of an inside length horizontally, slightly greater than the length of the wrapped article and of a width horizontally sufficient to allow the articles to move upwardly therein without undue friction. The said guide or stack f is provided with a passageway through its base for a reciprocatory carrier or stacker-lever f' of the stacker. This lever f' is pivoted at, f^2 , between lugs, f^3 , on a ram, f^4 , and a spring, f^5 , is provided between the end, f^6 , of the carrier, f' , and the ram for accelerating the downward motion of the lever after the goods have been deposited within the stacking chute or stack f . A pawl or dog, f^7 , is pivoted to the ram at, f^8 , and is drawn toward the pivot, f^2 , by a spring, f^9 , and is adapted to hook over a pin or stud, f^{10} , on the side of the arm, f^6 , to hold the lever f' up when delivering goods to the stacking chute. The carrier f' is held up in position to receive the wrapped article in the depression, f^{11} , thereof, the ends of the said article extending laterally beyond the carrier at each side thereof, and above the shelves, f^{12} , near the bottom of the stack f . Beyond the depression, f^{11} , the carrier is provided with a table, f^{13} , and below the end of the table, f^{13} , is a cam, f^{14} , attached thereto, the said cam being adapted for co-action with the fixed stud or roller, f^{15} , on the frame or table, 5. The ram, f^4 , is moved to and fro by means of the bell lever, f^{16} , which is fulcrumed at, f^{17} , and engages by the slot and pin, f^{18} , with said ram. The other end of the said lever, f^{16} , is pivotally connected at, f^{19} , with a link, f^{20} , which is pivotally connected at, f^{21} , with the pusher d aforesaid, the arrangement being such that as the said pusher d makes its return or dead stroke the ram is advanced to carry the wrapped article under the stack f .

- f. The front wall of the stack f is curved outwardly at, f^{22} , for the purpose of guiding the articles into the stack with greater certainty.
- 5 The operation of the stacker is as follows: The stacker-lever f' , in the position thereof shown in Fig. 6, is supposed to be moving to the left and to have a wrapped article in the recess, f^{11} , thereof, and as the 10 ram, f' , is advanced from the position thereof shown in Fig. 3, to the right the carrier f' carries the wrapped article in the said recess, f^{11} , above the shelves, f^{12} , aforesaid; before the ram completes its forward 15 or working stroke, however, the pawl, f^{10} , strikes a fixed corner, f^{24} , on the machine and is disengaged from the pin, f^{10} , aforesaid, whereupon the spring, f^5 , raises the end, f^6 , and depresses the end or table, f^{13} , 20 more than enough to disengage the wrapped package from the recess or depression, f^{11} , thereby depositing the said package on the said shelves, f^{12} . It should be remarked that if there are any packages in the stack f , 25 such packages are lifted and held above the top, or at least flush with the top of the wrapped package in the depression, f^{11} , as the said ram advances, whence it results that the wrapped packages are placed in 30 the stack from underneath. On the return stroke of the ram and very near the end thereof, the cam, f^{14} , strikes the stud or roller, f^{15} , and the stacker lever is raised to the position thereof shown in Fig. 6, and 35 the pawl, f' , engages with the pin, f^{10} , to retain the stacker lever in the position shown in Fig. 6. The articles are fed from the channel e out over the stacker lever f' and under the rolls, f^{23} , as the ram is on its 40 return or dead stroke, and are received by the flat surface, f^{20} , of said lever f' . The articles are prevented from moving with the lever f' at such times, however, by the fixed stop, f^{27} . The rollers, f^{23} , are journaled on studs 45 on a lever, f^{28} , fulcrumed at, f^{29} , and having a weight, f^{30} , adjustable therewith. The articles drop into the recess, f^{11} , one for each stroke of the ram as the lever, f' reaches the end of its return or dead stroke.
- 50 The devices shown for feeding the labels, one by one, underneath the plunger head b will now be described, reference being had more particularly to Figs. 2, 4, 5 and 7. The labels with their printed faces down 55 are placed in the guideway formed by the fingers h h' and rest upon the belts, h^2 , of rubber or other suitable material; the belts, h^2 , run upon the pulleys, h^3 , h^4 . The pulleys, h^3 , are fast upon a shaft, h^5 , which is 60 journaled in the side frames, h^8 , and forms the driving member of the combination. The said shaft, h^5 has fast thereon a ratchet wheel, h^7 , and the said shaft, h^5 , alongside the ratchet wheel, h^7 , carries a gear wheel, h^8 , which is loose thereon. The gear, h^8 ,

carries a spring-pawl, h^{20} , pivoted thereon, which is adapted to engage with the wheel, h^7 , aforesaid. The tail of this pawl extends beyond the periphery of the gear, h^8 , and is adapted to co-act with a cam, h^{30} , so as to be disengaged, while in contact with said cam, from the said wheel, h^7 , whence it results that the continuous motion of the gear, h^8 , gives only an intermittent motion to the pulleys, h^3 , and the parts operated thereby. 70 The gear, h^8 , is rigidly connected with a sprocket wheel, h^9 , which is free to turn on the shaft, h^5 . The sprocket, h^9 , is driven by a chain, h^{10} , and sprocket, h^{11} , from a shaft connected by beveled gears, h^{12} , with the shaft D aforesaid. Above and co-acting with the belts, h^2 , are stationary rolls, h^{13} , and between the pulleys, h^3 , aforesaid are disks or rollers, h^{14} . The disks, h^{14} , project beyond the belts, h^2 , and co-act with 80 friction disks, h^{15} , whose peripheries are covered with soft rubber or other suitable friction material to feed the label forward and down between the rollers, h^{16} , h^{17} , a guide, h^{18} , being employed to guide the forward end of the label down between the rollers, h^{16} , h^{17} , and to direct the said label along the table, 4, and under the feed rolls, h^{19} . The rollers, h^{19} , are fast upon a shaft, h^{20} , which is driven from the gear, h^8 , by a 90 train of gears, h^{21} . The shaft, h^{20} , forms the axis of motion of the lever, h^{22} , at the free end of which lever is a rotary shaft, h^{23} , on which is fast a roller, h^{24} . The shaft, h^{23} , is driven from the shaft, 29, by the 100 train of gears, h^{25} . Directly under the drop roller, h^{24} , is placed a roller, h^{26} , in the slot or opening in the table, 4. The lever, h^{22} , is normally drawn downward by the spring, h^{27} . Near its end, the lever, h^{22} , is provided with a pin, h^{28} , which coacts with the cam, a^{10} , on an arm all extending from the pusher a aforesaid. For the purpose of agitating the wrappers in the guide, h , an agitator, h^{31} , is journaled upon the axis of 110 the roller, h^{18} , aforesaid and is provided with an extension, h^{33} , the latter being for co-action with the cam or finger, h^{35} , which lifts the agitator. The agitator may be returned to normal position by gravity or by 115 a spring, h^{34} . The cam, h^{30} , may be adjustable as to position and length.

The operation of the label-feeding devices is as follows: At the periodic operation of the pawl and ratchet mechanism connecting 120 the shaft, h^5 , with the gear, h^8 , the bottom label of the stack is carried by the pulleys and belts under the rollers, h^{16} , and between the feed rolls, h^{14} , h^{16} , and thence downward between the feed rolls, h^{16} , h^{17} , 125 along the guides, h^{18} , and under the feed rolls, h^{19} , the printed face of the label being downward. When the pusher a is at the end of its return, the cam, a^{10} , co-acting with the pin, h^{28} , has raised the roller, h^{24} , out of 130

- contact with the roller, h^{26} , and the label fed forward by the roller, h^{19} , rests upon the roller, h^{26} . As the pusher a begins to move forward on its operative stroke, and as soon as the cam, a^{10} , releases the roller, h^{24} , and allows it to drop, the continuously rotating roller, h^{24} , coacting with roller, h^{26} , feeds the label forward over the bridge piece, a^9 , aforesaid and against a fixed portion of the machine so that, on the return stroke of the pusher a and the bridge-piece, a^9 , the label is retained in position underneath the wrapper w and the article p as shown in Fig. 14.
- 15 No claim is made herein to the label or sheet feeding mechanism *per se*, as the same forms the subject-matter of my pending application filed April 16, 1909, Serial Number 490,313; sheet feeding mechanism.
- 20 What I claim as new and desire to secure by Letters Patent of the United States is—
1. In a wrapping machine, the combination of means for holding a packet of loose leaves, means for removing said leaves, one by one, from the bottom of said packet and feeding them forward, a roller upon which said feeding means deposits said leaves, a vertical passageway adjacent to said roller, a pusher for pushing articles over said passageway and provided with a bridge piece for covering and uncovering said passageway, a drop roller for co-action with the aforesaid roller, means whereby said pusher raises and lowers said drop roller to cause the same to feed the leaves upon said bridge piece while the latter covers said passageway, and means for moving the article through said vertical passageway to fold the leaves about said article.
  2. In a wrapping machine, the combination with a plate provided with a vertical passageway, of a pusher for pushing articles over said passageway and provided with a bridge-piece for covering said passageway at such times, means for feeding a label or wrapper upon said bridge-piece while the same covers said passageway, and means for moving the articles through said vertical passageway to fold the leaves about said articles.
  3. In a wrapping machine, the combination with a plate or table having a vertical passageway therethrough, a pusher for pushing articles over said passageway and provided with a bridge-piece for covering said passageway at such time, a sheet-feeding mechanism controlled by said pusher for feeding sheets upon said bridge-piece beneath the articles while said bridge-piece covers said passageway, and means for moving the articles through said vertical passageway to fold the leaves about said articles.
  4. In a wrapping machine, the combination with a plate or table having a vertical
- passageway therethrough, of a pusher for placing articles over said passageway and provided with a bridge-piece for covering said passageway while so doing, a label or wrapper feeding mechanism provided with a drop roller for feeding said labels or wrappers, a cam connected to and moving with said pusher for lowering and raising said drop roller, and means for moving the articles through said vertical passageway to fold the leaves about said articles.
5. The combination with a stack provided with shelves fixed at opposite sides near the bottom thereof and having an opening therethrough at such point, of reciprocatory means for lifting the articles in said stack and depositing another upon said shelves underneath the same.
6. The combination of a stack having an opening near the bottom thereof and provided with shelves at opposite sides of said opening, and an end-wise reciprocating lever having a horizontal fulcrum and provided with a table for sustaining the articles in said stack and with a recess for receiving the article and placing the same upon said shelves underneath the articles in said stack, with means for raising and lowering said lever.
7. The combination with a stack having an opening near the bottom thereof and provided with shelves at opposite sides of said opening, of a reciprocatory ram, a lever fulcrumed on said ram and provided with a table and with a package-receiving depression, a dog for holding said lever in its elevated position, means for releasing said dog at the end of the working stroke of the said ram, and means for raising said lever at the end of the dead stroke of said ram and reengaging it and said dog.
8. The combination with a stack having an opening near the bottom thereof and provided with shelves at opposite sides of said opening, of a reciprocatory ram, a lever fulcrumed on said ram, and having a package-sustaining table and a package-receiving depression, releasable means connecting the said lever with said ram to release the lever at the end of the working stroke of the ram, and cam devices for lifting the lever to its working position at the end of the dead-stroke of the ram.
9. The combination of a stack with an opening near the bottom thereof and provided with shelves at opposite sides of said opening, of an endwise-movable lever having a horizontal fulcrum and provided with a package-receiving recess in its upper face and passing through said opening, releasable means for retaining said recessed end of said lever in its upper or working position and releasing the lever at the end of its working stroke, a cam on the underside of said recessed end of said lever, and a fixed

abutment against which said cam strikes at or near the end of the dead stroke of said lever.

10. The combination with a stack provided with an opening near the bottom thereof, of a reciprocatory stacker-lever, means for laying wrapped articles upon said lever, pressure rolls for holding down the articles upon said lever, and a pivoted lever carrying said rolls, whereby said rolls may be thrown out of operative position.

11. The combination with a stack provided with shelves at opposite sides thereof and having an opening therethrough at such point, of an endwise-shiftable and rocking lever for lifting the articles in said stack and depositing another upon said shelves underneath such articles.

12. The combination with a stack provided with shelves at opposite sides thereof,

of a lever having a horizontally-movable fulcrum and adapted to raise the articles in said stack and deposit thereunder another article on said shelves, and operating means therefor.

25

13. The combination with a stack provided with shelves at opposite sides thereof, of a rocking and endwise movable lever adapted to lift the articles in said stack and deposit thereunder another article on said shelves, means for moving said lever endwise, and means for rocking said lever.

In witness whereof I have hereunto set my hand in the presence of two subscribing witnesses.

THEODORE G. McGIRR.
